AUTOMATIC BOBBIN-EXCHANGING DEVICE FOR LOOMS.

1,041,304.

Specification of Letters Patent.

Patented Oct. 15, 1912.

Application filed October 5, 1911. Serial No. 652,954.

To all whom it may concern:

Be it known that I, ALBERT GEORG KOECHLIN, a citizen of the Swiss Republic, and resident of Basel, Switzerland, have invented new and useful Improvements in Automatic Bobbin-Exchanging Devices for Looms, of which the following is a full, clear, and exact specification.

Since the use of looms having automatic weft spool or bobbin change has become more usual, a great variety of types of magazine have been suggested in which the weft spools or bobbins are stored before being used, and a great variety of transferring mechanisms have been suggested for conveying these spools or bobbins from the magazines to the usual transferrer. The magazines hitherto known are either of the well known revolver type or are arranged as fixed square chambers in which the spools or bobbins rest singly in grooves or runways and in which movable members are arranged such as flaps, movable channels and the like which always keep the weft spools or bobbins separated from one another until they pass to the usual transferrer. All magazines of the last kind feed a revolver type drum lying underneath them whereby the spools are generally passed to this drum through a closed channel.

The present invention relates to an improved and greatly simplified weft spool magazine which is specially adapted for directly conveying the spools to the usual transferrer and moreover the arrangement of the conveying or guideway from the magazine to the transferrer is a greatly simplified one.

In the bobbin exchanging device according to the present invention the weft bobbin magazine consists of a box without any inner partition-wall, but provided in the well known manner with a sloping base. In this box the weft bobbins are freely located one over the other, and a stationary restraining wedge is arranged internally at the front side of the box above a lower exit opening for the bobbins in order to hold back the bobbins, to sustain their pressure from above and from behind and to break up or separate the layers one from the other. A guide for the spools of the lower layer is arranged on the base of the box. Furthermore, the bobbins lying on the guide channel from the magazine to the transferrer are

relieved of the greater part of the pressure of the rest of the spools in the magazine as the part of the guide channel contiguous to the base of the box lies somewhat beneath the exit opening in it. Owing to this arrangement of guide channel, the spools or bobbins passing along it can move forward smoothly and without hindrance and the guide channel is further preferably provided with guide means to keep the bobbins in their correct position.

The accompanying drawing shows several constructional forms of the invention in which—

Figure 1 is a vertical section of a preferred arrangement according to the present invention. Fig. 2 is a plan view of the same. Fig. 3 is a cross section on the line A—B of Fig. 1. Fig. 4 is a sectional elevation, and Fig. 5 is a plan view of a second constructional form. Fig. 6 shows a third constructional form.

In the drawing, *a* (Figs. 1-3) is an oblong box open at the top without any inner partition-wall, in which the weft spools or bobbins are arranged in layers parallel one above the other. The width of the box *a* corresponds approximately to the length of the bobbins. This box is provided in the well known manner with a sloping base leading to an exit opening *b* for the bobbins at the front end of the box. On the inner side of the front wall of the box *a* is arranged above the opening *b* an internally protruding stationary retaining wedge *c* which forms an inner guide-channel ahead of the opening *b* and at the same time serves to free the opening from the pressure of the bobbins from behind and from above and also to separate the layers of bobbins pressing forward so that the bobbins pass singly to the exit opening *b*.

A guide rail *d* is arranged on the base of the box *a* which serves to guide the bobbins of the lowest layer as the head of the bobbins slides along said rail *d* (Fig. 3). This rail prevents the bobbins from lying obliquely across the floor of the box *a* and insures that the bobbin passing forward shall always be in a straight position. In order to prevent two bobbins from passing at the same time through the opening *b* of the magazine box *a*, this is provided on the outside with a retaining flap *e* which is suspended on a fixed point and by its own

weight is so limited in its outward movement that it just allows of the escapement of one bobbin at a time.

5 A transferring guide channel f is arranged passing from the box a to the filling place under the usual transferrer g . The part of this channel lying contiguous to the opening b has a slope somewhat corresponding in inclination to the base of the box or receptacle a , but lies somewhat below it. This is so that the bobbins on the transferring channel will be at least relieved of the greater part of the pressure of the bobbins in the magazine so that they may easily and 10 without hindrance slide on to the transferring channel. They are guided on the above mentioned part of the transferring channel which consists of an open and accessible groove (see Fig. 1), by means of a guide rail d^1 in the same manner as they are guided on the floor of the magazine box or casing. The transferring channel is bent on one side around the transferrer g as may be seen from Fig. 1.

15 25 The above stated constructions are modified in the construction according to Figs. 4 and 5 in that the transferring or bobbin conveying channel f^1 is brought directly up to the transferrer g , that is to say is not bent round. The exit opening b^1 of the magazine may also be arranged on the base of the bobbin box a instead of in the front wall, as shown in Fig. 6. The remaining details of construction are the same as stated above except that in this case the front retaining flap is not necessary.

20 30 35 In all the above mentioned cases the bobbins are brought from the magazine to the transferrer directly, that is to say without the auxiliary aid of a revolving transporting drum.

35 40 45 An important difference between the described arrangements and those hitherto known applies in that there are no bobbin partitions or movable parts in the magazine and nevertheless the bobbins are arranged singly therein and straightly conveyed one by one to the desired position where they are pushed by the usual transferrer into the 50 working shuttle of the loom. The bobbins are after the weft thread ends have been wound round the end of the weft carrier in the known way, or otherwise attached thereto, freely laid by the operator into the magazine which may be of any size without any special vertical guiding for the bobbins, and this box may then be directly transferred on the loom.

55 60 65 Finally, several modifications may be mentioned. The inclination of the base of the box or magazine and the part of the transferring channel abutting against it may be altered according to requirements.

What I claim is:

65 1. In an automatic weft bobbin exchang-

ing device for looms, a bobbin magazine consisting of a box without any inner partition wall for receiving a plurality of superposed layers of bobbins, said box having a slightly inclined base and being provided above an exit opening for the bobbins with an internally protruding retaining wedge, forming an inner guide-channel ahead of said opening and designed to relieve the bobbins near the latter from the pressure of the other bobbins in the box and to separate the bobbin layers near said opening, said box being provided at its base with a guide rail for the bobbins of the lowest layer, a transferrer for transferring the bobbins into the working shuttle and an inclined guide-channel for conveying the bobbins from the box directly to said transferrer, said guide-channel having its end contiguous to the box somewhat below the base thereof, substantially as and for the purpose described.

2. In an automatic weft bobbin exchanging device for looms, a bobbin magazine consisting of a box without any inner partition wall for receiving a plurality of superposed layers of bobbins, said box having an inclined base and being provided above an exit opening for the bobbins with an internally protruding retaining wedge, forming an inner guide-channel ahead of said opening and designed to relieve the bobbins near the latter from the pressure of the other bobbins in the box and to separate the bobbin layers near said opening, said box being provided at its base with a guide rail for the bobbins of the lowest layer, a transferrer for transferring the bobbins into the working shuttle and an inclined guide-channel for conveying the bobbins from the box directly to said transferrer, said guide-channel having its end contiguous to the box somewhat below the base thereof, and being also provided with a guide rail for the bobbins to keep them in their correct position, substantially as and for the purpose described.

3. In an automatic weft bobbin exchanging device for looms, a bobbin magazine consisting of a box without any inner wall for receiving a plurality of superposed layers of bobbins, said box having an inclined base and being provided above an exit opening for the bobbins with the internally protruding retaining wedge, forming an inner guide-channel ahead of said opening and designed to relieve the bobbins near the latter from the pressure of the other bobbins in the box and to separate the bobbin layers near said opening, said box being provided at its base with a guide rail for the bobbins of the lowest layer, a transferrer for transferring the bobbins into the working shuttle and an inclined guide-channel for conveying the bobbins from the box directly to said transferrer, said guide-channel having its end contiguous to the box somewhat below the base thereof, substantially as and for the purpose described.

base thereof, a retaining flap being arranged on the outside of the exit opening in the box, substantially as and for the purpose described.

- 5 4. In an automatic weft bobbin exchanging device for looms, a bobbin magazine consisting of a box without any inner partition wall for receiving a plurality of superposed layers of bobbins, said box having a slightly 10 inclined base and being provided above an exit opening for the bobbins with an internally protruding stationary retaining wedge, forming an inner guide-channel ahead of said opening and designed to relieve the bobbins near the latter from the pressure of the other bobbins in the box and to separate the 15 bobbin layers near said opening, said box be-

ing provided at its base with a guide rail for the bobbins of the lowest layer, a transerrer for transferring the bobbins into the working shuttle and an inclined guide-channel for conveying the bobbins from the box directly to said transerrer, said guide-channel having its end contiguous to the box somewhat below the base thereof, substantially as and 20 25 for purpose described.

In witness whereof I have hereunto signed my name this 23d day of September 1911, in the presence of two subscribing witnesses.

ALBERT GEORG KOECHLIN.
